ABSTRACT: Carbon dioxide snow from an overlying snow tower is intermittently fed into an extrusion chamber wherein a ram is reciprocated by a hydraulic drive. The snow is compressed at a pressure of at least 1 ton per square inch and extruded through a die having a plurality of apertures to make rods of dense supercooled CO₂ that break into short nuggets. The size and number of the die apertures are controlled relative to the cross-sectional area of the ram. A gas reservoir is provided in fluid communication with the rear end of the extrusion chamber which precludes the entry of humidity-bearing air into the cold extrusion chamber.

FIG.2

APPARATUS FOR MAKING SOLID CARBON DIOXIDE

This invention relates to the production of solid carbon dioxide and, more particularly, to a process for the production of solid carbon dioxide nuggets and to apparatus for performing such a process.

Solid carbon dioxide has the advantage of exceptionally good weight efficiency for a refrigeration media; however, the problems attendant to providing useably shaped solid carbon dioxide at the point of end use have thus far prevented solid carbon dioxide from attaining a very large share of the refrigeration market. Although solid carbon dioxide has long been made available in the form of fairly large blocks, either a sawing, pulverizing or a grinding operation has been generally required to reduce such blocks to a size suitable for the actual end refrigeration use. Such operations both incur a labor cost for manpower and give rise to a loss in the actual product due to increased sublimation of the solid carbon dioxide during and after the operation. Although various attempts have been made to provide processes and apparatus for providing solid carbon dioxide in more usable form, none have achieved substantial commercial success.

It is the object of the present invention to provide an improved process for providing solid carbon dioxide nuggets of a shape which facilitates easy handling thereof and to provide apparatus for performing such a process. Another object of the invention is to provide a dependable, semicontinuous, automatic apparatus for the efficient production of nuggets of solid carbon dioxide. These and other objects of the invention should be apparent from a reading of the following detailed description of one illustrative apparatus embodying various features of the invention, in conjunction with the accompanying drawings wherein:

FIG. 1 is a vertical sectional view of apparatus for the production of solid carbon dioxide nuggets embodying various of the features of the invention, which view is taken generally along section line 1-1 of FIG. 2 and includes a diagrammatic representation of auxiliary equipment that would usually be included with such an operating apparatus; and

FIG. 2 is an enlarged front elevational view of the apparatus shown in FIG. 1.

An extrusion apparatus 11 is illustrated which is designed for automatic, semicontinuous extrusion of a plurality of rods of dense carbon dioxide through apertures in an extrusion die 13. The apparatus 11 includes a ram 15 which is driven in reciprocating movement by a hydraulic drive unit 17. In FIG. 1, the ram 15 is shown in its extended position in its location in an extrusion chamber 19 of the apparatus. In the extended position, the ram 15 blocks an entrance 21 to the extrusion chamber 19 from an upstanding snow tower section 23 wherein liquid carbon dioxide is flashed to a mixture of carbon dioxide snow and gaseous carbon dioxide by expansion through a suitable nozzle 25. The snow falls to the bottom of the snow tower section 23 where it accumulates until the ram 15 is retracted, at which time it falls into the extrusion chamber 19 to be compressed by the ram on its next power stroke. The downward flaring configuration of the inner wall of the snow tower section 23 helps assure the release of the snow, allowing it to fall by gravity into the extrusion chamber 19.

It has been found that by providing a hydraulic drive unit 17 which will apply sufficient force to said ram 15 so that the ram will exert a pressure of at least about 1 ton per square inch upon the compacted solid carbon dioxide at the end of the extrusion chamber 19, dense rods of supercooled carbon dioxide are extruded. Moreover, it has been found that if a predetermined relative relationship is maintained between the cross-sectional area of the ram 15 and the individual size and the total number of apertures in the extrusion die 13, efficient operation of the apparatus 11 in the extrusion of dense carbon dioxide rods is obtained. Inasmuch as the temperatures involved are well below the freezing point of water, it has also been found important that humidity-bearing air be excluded from the operational portions of the apparatus lest ice forma-

tion result which might well deter the performance of the apparatus and/or require its shutdown. It has been found that, if the extrusion chamber 19 is closed to the atmosphere and if a separate auxiliary gas reservoir 27 of sufficient volume is provided, entry of the atmospheric air into the extrusion chamber 19 is effectively avoided.

Now referring more specifically to the details of the drawings, the illustrated apparatus 11 includes a base 29 upon which the extrusion chamber 19 is supported. The base 29 is hollow and also serves as the gas reservoir 27. The base 29 may be constructed in any suitable manner to provide a gastight central chamber as by welding together two facing channels and welding plates at the opposite ends thereof. A plurality of feet 31, suitably attached as with screw threads or by welding, support the base 29 above the level of the floor.

The extrusion chamber 19 is defined by an assembly comprising a main horizontal tubular body 33 containing the upper generally circular entrance 21 which is defined by an upstanding collar support section 35 having a circular flange 37 at its upper end. The tubular body 33 is mounted on the base 29 by a rear mounting plate 39 and a front mounting plate 41.

The rear mounting plate 39 contains an annular cavity in the forward surface thereof which receives the rear end of the tubular body 33 and a suitable seal, such as an "O"-ring, may be disposed in the cavity to seal the extrusion chamber 19 at this point from the outside atmosphere. The rear plate 39 is suitably secured to the base 29, as by a pair of bolts extending upward through the upper wall of the base into tapped holes in the bottom of the plate. Two holes, which are drilled at right angles to each other, provide a passageway 43 in the plate 39 extending from the front surface of the plate downward to a tapped hole which receives the threaded end of a pipe 43a that depends into the gas reservoir 27 in the base. Thus the passageway 43 serves to place the reservoir 27 in fluid communication with the rearward portion of the extrusion chamber 19 wherein the ram 15 reciprocates.

Coaxial with the ram 15 and extending from the left-hand side thereof (as viewed in FIG. 1) is a power transmission rod 45. Although the ram 15 might be machined from a single piece of steel which would then be suitably attached to the power transmission rod 45, in the illustrated embodiment, the ram 15 is made, for manufacturing convenience, from a series of separate rings 46 which are received on an end portion 47 of reduced diameter of the power transmission rod. The individual rings 46 are held in place by an endpiece 49 having a threaded central hole that is screwed onto mating threads provided on the terminal portion of the reduced diameter section 47 of the power transmission rod. The threaded endpiece 49 is locked in place by a setscrew 51. A pair of front seals 53 are received in a peripheral recess provided at the rear surface of the end piece 51 and in the region provided by making the forwardmost ring 46 of a lesser diameter. A rider strip 55 is provided near the rear end of the ram 15, and no seal is provided at this location although there is a fairly close sliding fit between the rear end of the ram and the extrusion chamber wall.

The power transmission rod 45 extends through a central opening in the rear mounting plate 39, and a seal and bushing assembly 57 is carried by the rear mounting plate 39 to support, guide and seal the power transmission rod at this location. The hydraulic drive unit 17 includes a double-acting hydraulic cylinder 59 which is connected by suitable valving arrangement (not shown) to a source of high-pressure hydraulic fluid, such as a motor-driven pump 61. The hydraulic cylinder 59 includes a forwardly extending piston rod 63 which is coaxial with the power transmission rod 45 and which is connected thereto via a suitable connector assembly 65. The hydraulic cylinder 59 is also suitably supported on the base 29 by mounting plates 67 and 69.

Disposed at the forward end of the extrusion chamber 19 is an expanding throat member 71 which includes an upstanding circular flange of a suitable diameter to fit over the exterior

surface of the circular front end of the main tubular body 33. The inner surface of the throat member 71 has the general configuration of a frustum of a cone, and it is employed in order to provide a smooth transmission from the extrusion chamber 19 of a given diameter to the extrusion die 13 having an apertured region of a larger diameter, for reasons explained hereinafter.

As best seen in FIG. 2, the extrusion die 13 comprises a generally rectangular-shaped block of steel containing a plurality of apertures 73 which are regularly spaced within a central circular region. Apertures 73 of various shapes may be used; however, simple drilled holes are usually employed. The extrusion die 13 is machined to provide a protruding short plug portion at the rear surface thereof which is received within the end of the throat member 71 as shown in FIG. 1. The extrusion die 13 is supported by four threaded studs 75 extending from the front mounting plate using hexhead nuts 77 and suitable locking washers. The front mounting plate 41 is suitably attached to the base 29 in the same manner as the rear mounting plate, as by upwardly extending bolts. The front mounting plate 29 contains a central opening of suitable size to accommodate the front end of the main tubular body 33 which passes therethrough. When the assembly of the structure is complete, four welded tie rods 79 are installed, using suitable nuts which screw onto threaded portions thereof adjacent the front and rear mounting plates 39 and 41 and the hydraulic cylinder mounting plate 67, to add overall rigidity to the structure.

The snow tower section 23 comprises a generally tubular column 81 which is designed to fit downward into the collar support section 35 and terminate a short distance above the upper surface of the ram 15 at the location of the upper entrance 21 to the extrusion chamber 19. A peripheral recess in the outer surface of the column accommodates a split ring 83 which is seated in a suitable circular recess provided in the upper surface of the upper flange portion 37 of the collar support section 35. The column 81 is clamped in this location by a holdown ring 85 which contains a recess in its undersurface that receives the upper circumferential edge of the split ring 83. Aligned holes in the holdown ring 85 and the upper flange portion 37 of the collar support section facilitate the attachment of the ring via nuts and bolts, and a suitable annular gasket is provided therebetween. The outer surface of the column 81 is also provided with a pair of peripheral recesses which accommodate O-rings 87 that provide a seal between the outer surface of the column and the inner surface of the collar support section 35.

The upper end of the column 81 is partially closed by a cap plate 89 which carries a depending tube 91 leading upwardly to a central aperture in the cap plate 89. The cap plate is suitably attached by a plurality of bolts which extend downward into the upper end of the column 81. An upstanding internally threaded coupling 93, which is suitably attached to the upper surface of the cap plate 89, provides a connection between the top of the snow tower 23 and a gas return conduit 95. As best seen in FIG. 2, the nozzle 25 enters the column 81 in a nonradial direction so that the snow which is created is directed with a spiral motion against the inner wall of the column 81. This creates a centrifugal separation effect with the solid snow tending to travel along the column wall while the gaseous carbon dioxide remains primarily in the central region from which it exits by entering the bottom of the depending tube 91, which leads upward and out of the top of the column 81 into the return gas conduit 95. Because spiral movement of the snow along the wall is created, an excellent separation of snow and gas is achieved as the snow gravitates to the bottom of the column. As a result of achieving such an effective separation, the nozzle can be operated at a fairly high capacity.

In the overall operation of the extrusion apparatus 11, liquid carbon dioxide from a storage vessel 101, whereat it is maintained at a pressure between about 220 and 300 p.s.i.g., is fed to the nozzle 25 through a feedline 103. If there is a considera-

ble distance between the storage vessel 101 and the extrusion apparatus, a pump may be included in the line 103. In order to subcool the incoming liquid, the feedline 103 leads to a spiral coil of tubing 105 which is in heat exchange contact with the outer surface of the column 81 which is made of a material, such as aluminum, that is a good conductor of heat. The passage of the relatively warm liquid through this spiral coil 105 has the dual effect of subcooling the liquid and warming the column 81, which further reduces any tendency the snow might have to adhere to the inner surface of the column and create a potential blockage. The liquid exiting from the coil 105 flows through a heat exchanger 107 where some of the cooling potential of the cold gas from the snow tower is utilized to further subcool the liquid. From the heat exchanger 107 the liquid passes through a valve 109 which leads to the nozzle 25. Proper adjustment of the valve 109 provides the desired amount of flow of liquid to the expansion nozzle 25 through which it is sprayed to create snow and cold carbon dioxide gas at the rate desired.

The gas exiting from the upper end of the column 81 merges with gas flowing in a line 111 leading from the extrusion chamber 19 at a region near the right-hand end thereof where carbon dioxide gas is liberated from the snow during the compressive action of the ram 15 on the snow charge in the extrusion cylinder. Small holes in the wall of the tubular body 33 at this region lead to a circumferential cavity in the front mounting plate 41 at the central opening therethrough. The cavity connects via a drilled hole 113 with the line 111. The combined gas streams pass through the heat exchanger 107 and pick up some heat from the liquid that is being subcooled. The cold gas from the heat exchanger 107 flows through conduit 114 where it passes through a heat exchanger 115 on its way to a compressor 117. The gas leaving the heat exchanger 115 is at a pressure of about 30-40 p.s.i.g., and the compressor 117 raises the pressure to slightly above 300 p.s.i.g.

The gas picks up a considerable amount of heat in the compressor 117, and it flows first through a water-cooled heat exchanger 119 on its way back to the heat exchanger 115 wherein it loses more of its sensible heat to the low-pressure cold gas stream flowing toward the compressor 117. The high-pressure gas exiting from the heat exchanger 115 flows through a conduit 121 to a condenser 123 which is cooled by a refrigeration unit using a freon refrigerant. Freons are polyhalogenated derivatives of methane and ethane containing fluorine and, in most cases, chlorine or bromine. Monochlorodifluoromethane (Freon-22) is one of the freons most commonly used. Refrigeration units of this type are commercially available.

The condenser operation is controlled so that the gas is substantially entirely condensed to liquid before reaching a return line 127 leading to the storage vessel 101. A pressure-regulating valve 129 in the return line 127 maintains a pressure of at least about 300 p.s.i.g. in the line 127. It has been found that the freon refrigeration unit functions far more efficiently if the system is operated at a pressure of at least about 280 p.s.i.g. Most large CO_2 storage vessel systems operate at a pressure varying from about 240 to 280 p.s.i.g., depending upon supply conditions and local climate; however, pressures are usually not used above about 300 p.s.i.g. Because the pressure within the usual storage vessel 101 does not normally exceed 280 p.s.i.g., it is not considered economical to design the overall plant to function at much higher pressures. The pressure within the condenser 123 is preferably maintained at a value of about 300 p.s.i.g. by the installation of the pressure-regulating valve 129 in the return line 127 that reads the pressure in the condenser via a pilot line (not shown). By operating the condenser at such an elevated pressure, somewhat less heat need be withdrawn from the compressed gas because the change to the liquid phase takes place at a higher temperature. More importantly, this facilitates the higher temperature, more efficient operation of the refrigeration unit 125 utilizing the joule-thomson expansion of freon refrigerant because such units operate progressively less efficiently at progressively

lower temperatures where isenthalpic (joule-thomson) expansion departs more and more from isentropic (perfect) expansion. The liquid passing through the valve 129 is delivered to the storage vessel 101 at a location above the liquid level therein.

As previously indicated, the ram 15 is driven in reciprocating movement by the hydraulic drive unit 17 which includes the double-acting hydraulic cylinder 59. A suitable valving arrangement (not shown) is provided to drive the ram 15 forward on its power stroke until it reaches the point of desired extension, which is shown in FIG. 1. At this point, the hydraulic fluid is shifted to the other end of the double-acting cylinder, and the ram 15 is retracted. As the front edge of the ram 15 passes under the entrance 21 from the snow tower 23, the snow which has accumulated at the bottom thereof falls via gravity into the extrusion chamber 19 and continues to fall thereinto until the ram again closes the entrance on its next power stroke. As the ram 15 moves forward, the snow in the extrusion chamber 19 is carried along and compressed against the charge of solid carbon dioxide which fills the hollow region of the throat member 71 adjacent the extrusion die 13. As compression of the snow takes place, the gaseous carbon dioxide present escapes through the openings in the extrusion chamber and exits through the hole 113 leading to the line 111 which merges with the line carrying the gas leaving the top of the snow tower.

As the ram 15 nears the end of the power stroke, the solid carbon dioxide which has previously been built up in the throat member 71 is displaced by that being carried along by the ram and is thus forced through the apertures 73 in the extrusion die 13 in the form of rods of dense solid carbon dioxide. These rods are relatively fragile in tensile strength and tend to break of their own weight to form short rod sections which are termed "nuggets." If desired, a deflector (not shown) can be supported from the end of the extrusion die to assure that breaking of the rods occurs at about the desired length.

It has unexpectedly been found that the employment of the very high pressures which are available from the hydraulic drive system 17 not only produces a dense product (which has good space efficiency, i.e., B.t.u. per unit volume) but a supercooled product. It is found that a supercooling effect occurs when the ram 15 exerts a pressure of about 1 ton or more per square inch against the built-up mass of solid carbon dioxide in the throat member 71. The temperature depression of the nuggets results from the condition of very high compression which is established on the inlet side of the extrusion die while an essentially constant temperature is maintained as a result of the presence of the fairly large mass of compressed solid carbon dioxide in the throat member 71. When this high pressure is rapidly removed from the solid carbon dioxide as the rods pass through the die apertures, supercooling results. The supercooling is quite advantageous because, as a result of their supercooled characteristics, the nuggets have and will retain good strength and handleability.

Generally, pressures of about 1.2 tons per square inch are employed. In the illustrated embodiment, the ram 15 has a diameter of about 6 inches which is equal to a cross-sectional area of about 28.3 square inches. The hydraulic drive unit 17 employed is sufficient to drive the ram 15 with the force of about 70,000 pounds, or 35 tons, which is equal to about 1.24 tons per square inch of ram surface area. Operation near these conditions has been found to produce nuggets from the extrusion die which have a temperature as low as about 15° C. below the sublimation temperature of solid carbon dioxide at atmospheric temperature, i.e., -75.5° C. (-110° F.).

The number and the dimensions of the apertures 73 in the extrusion die can be varied and have an effect upon the efficiency of the operation of the extrusion apparatus 11. For example, when $\frac{1}{2}$ -inch diameter circular apertures 73 are employed, as was the case with the 6-inch diameter ram indicated above, the total cross-sectional area of the apertures should be between about 70 percent and about 80 percent of the cross-

sectional area of the ram, and is preferably equal to about 75 percent of the cross-sectional area of the ram. For example, for a 6-inch diameter ram, this would be a cross-sectional area of about 25.5 square inches. One-half inch diameter apertures

5 73 individually have a cross-sectional area of about 0.196 square inch, so that 130 apertures are employed in the extrusion die 13. In order to provide 130 $\frac{1}{2}$ -inch diameter holes in a circular region and still retain sufficient strength in the steel die to withstand the pressures which will be present in the extrusion chamber 19, the outwardly tapering throat member 71 is employed which flares outward to a circular opening having a diameter of about 8 $\frac{1}{4}$ inches. An extrusion apparatus 11 of approximately these dimensions employing a 6-inch diameter ram 15 having a stroke of about 12 inches can be operated to 10 reciprocate the ram through a complete cycle about every 8 seconds, and under these conditions it will extrude approximately 700 pounds dense supercooled carbon dioxide nuggets per hour, which is considered to be very efficient performance.

15 20 As previously indicated, the relative relationship between the total cross-sectional area of the apertures 73 to that of the ram 15 varies with the diameter of the individual apertures. As set forth above, for apertures about one-half inch in diameter, it is considered that the apertures 73 should cover a total area 25 equal to between about 70 percent and about 80 percent of the cross-sectional area of the ram. This relationship is inversely proportional. For slightly smaller apertures 73, for example apertures about three-eighths inch in diameter, the total 30 area occupied should be between about 80 percent and about 90 percent of the cross-sectional area of the ram, and preferably equal to about 85 percent of the cross-sectional area of the ram for efficient performance. For apertures slightly larger in diameter, for example about five-eighths inch 35 in diameter, it is considered that the total area occupied by the apertures should be between about 65 percent and about 75 percent of the cross-sectional area of the ram, and preferably equal to about 70 percent of the cross-sectional area of the ram 15 for efficient performance. It should be understood that 40 the foregoing figures are based upon simple drilled holes, and that if the die apertures were formed to converge, i.e., have a decreasing diameter, a larger relative percentage of apertures would be used.

45 In summary, the illustrated extrusion apparatus 11 operates efficiently in a semicontinuous, automatic fashion requiring little maintenance although temperatures in the neighborhood of -110° F. are experienced. As was previously pointed out, the extrusion chamber 19 is effectively sealed from the humidity-bearing atmosphere. The charge of solid carbon dioxide which is built up in the region of the throat member 71 provides a seal at the right-hand end of the extrusion chamber, as viewed in FIG. 1. The left-hand end of the extrusion chamber 19 is sealed at the point of penetration of the power transmission rod 45 by the bushing and seal assembly 57. The 50 pair of O-rings provide a seal between the outer surface of the column 81 and the inner surface of the upstanding collar support section 35 at the point of junction therebetween. As 55 previously indicated, the base 29 is made of a completely welded construction so as to provide a gastight interior chamber which serves as the gas reservoir 27.

60 As the ram 15 reciprocates within the extrusion chamber 19, it can be seen that the volume of the unoccupied region within the extrusion chamber varies from a maximum when the ram is in its extended position (as illustrated in FIG. 1) to a very small value when the ram is in its completely retracted position. The gas which fills this region between the rear surface of the ram 15 and the forward surface of the rear mounting plate 39, unless accommodated during the retraction 65 stroke of the ram, will be forced to bleed past the rear of the ram, which has a fairly close sliding fit with the extrusion cylinder wall, and past the bushing seal assembly 57 in the rear mounting plate 39. More importantly, when the ram moves forward on its next power stroke, a vacuum would be created 70 in this region that would result in gas bleeding back the op-

posite way. The gas which would bleed across the bushing and seal assembly 57 in the rear mounting plate 39 would be air from the atmosphere containing humidity. The water vapor in the air would turn to ice when exposed to the very low temperatures within the extrusion chamber 19, resulting in lower efficiency of the apparatus operation and potential maintenance and/or shutdown problems. These problems are alleviated in the illustrated extrusion apparatus 11 by providing the passageway 43 which leads downward from the front face of the rear mounting plate into the reservoir 27 and provides for the simple accommodation of the dry gas which will occupy this changing volume region within the extrusion chamber 19.

By providing such a gas reservoir 27 of sizeable volume, the gas which is forced from the left-hand end of the extrusion chamber 19 on the retraction stroke of the ram 15 is easily accommodated. The volume of displaced gas which must be accommodated is equal to the differential cross-sectional area between the ram 15 and the power transmission rod 45 times the stroke of the ram, and the gas reservoir 27 should have a volume at least twice as large as this displaced gas volume. In the illustrated extrusion apparatus 11, the volume of the gas reservoir 27 in the base 29 is about five times the displaced gas volume. Thus, assuming that the gas in the reservoir 27 and in the extrusion chamber 19 is at some given pressure when the ram 15 is in its fully extended position, after the ram has moved to its fully retracted position, the increase in pressure in the gas reservoir will be about 20 percent or less. This slight pressure increase does not result in any significant leakage past the bushing and seal assembly 57 during the short period in the cycle when the ram 15 is near the end of its retraction stroke.

Thus, the invention provides a process for the semicontinuous production of dense nuggets of supercooled carbon dioxide and apparatus for efficiently carrying out this process. One of the significant advantages is that the production of such dense supercooled nuggets of solid carbon dioxide produces an end product which is immediately ready for easy storage, distribution and handling at the use point for various refrigeration purposes. It is particularly advantageous that the nuggets are flowable and thus are susceptible to handling in the same manner as other granular solids.

Various of the features of the invention are set forth in the following claims.

What is claimed is:

1. Apparatus for extruding nuggets of solid carbon dioxide, which apparatus comprises means defining an extrusion chamber, a ram, a hydraulic drive unit connected to said ram for driving said ram in reciprocating movement within said extrusion chamber between an extended position and a retracted position, an extrusion die having a plurality of apertures disposed at one end of said chamber, a snow tower disposed vertically above said chamber-defining means and opening downward thereinto at a location between said die and said ram when said ram is in said retracted position, means associated with said snow tower for expanding liquid carbon dioxide under superatmospheric pressure to form snow into said extrusion chamber at a pressure of about 30-40 p.s.i.g., the total cross-sectional area of said ram, being generally in-

versely proportional to the size of the individual apertures, with circular apertures about five-eighths inch in diameter the total area of said apertures being between about 65 percent and 75 percent of the cross-sectional area of said ram, and

5 with circular apertures about three-eighths inch in diameter the total area of said apertures being between about 80 percent and 90 percent of the cross-sectional area of said ram, said hydraulic drive unit being designed to supply sufficient force to said ram to compress said snow and extrude dense rods of supercooled carbon dioxide through said apertures in said die.

2. Apparatus in accordance with claim 1 wherein the ratio of the total cross-sectional area of said die to said cross-sectional area of said ram is about 1.9.

15 3. Apparatus in accordance with claim 1 wherein a rod for reciprocating said ram extends exterior of said chamber-defining means at the rear end thereof opposite from that at which said extrusion die is disposed, wherein seal means is provided between said rod and said chamber-defining means, and

20 wherein gas reservoir means is provided which is in fluid communication with said extrusion chamber at a location near said rear end thereof.

4. Apparatus for extruding nuggets of solid carbon dioxide, which apparatus comprises means defining an extrusion

25 chamber, a ram, a hydraulic drive unit connected to said ram for driving said ram in reciprocating movement within said extrusion chamber between an extended position and a retracted position, an extrusion die having a plurality of apertures disposed at one end of said chamber, a rod for reciprocating

30 said ram extending exterior of said chamber-defining means at the rear end thereof opposite from that at which said extrusion die is disposed, seal means between said rod and said chamber-defining means, gas reservoir means which is in fluid communication with said extrusion chamber at a location near

35 said rear end thereof, a snow tower disposed vertically above said chamber-defining means and opening downward thereinto at a location between said die and said ram when said ram is in said retracted position, and means associated with said snow tower for expanding liquid carbon dioxide under superatmospheric pressure to form snow, said hydraulic drive

40 unit being designed to supply sufficient force to said ram to compress said snow and extrude dense rods of supercooled carbon dioxide through said apertures in said die.

5. Apparatus in accordance with claim 4 wherein said reservoir means comprises a hollow chamber sealed from the atmosphere having a volume at least about twice as great as the differential cross-sectional area between said ram and said rod times the length of stroke of said ram.

6. Apparatus in accordance with claim 5 wherein said hollow chamber is formed by an elongated base whereupon said extrusion chamber-defining means and said hydraulic drive unit are physically supported.

7. Apparatus in accordance with claim 6 wherein said chamber-defining means includes a horizontal generally tubular member supported between front and rear plates, wherein said seal means is carried by said rear plate and wherein said rear plate contains passageway means leading downward to said gas reservoir means in said supporting base.
